BERTIS H. URSCHEL, OF BOWLING GREEN, OHIO, ASSIGNOR TO URSCHEL ENGINEERING COMPANY, OF TOLEDO, OHIO, A CORPORATION OF OHIO

METHOD OF HEAT TREATING AXLES

Application filed August 26, 1930. Serial No. 477,813.

My invention has for its object to provide a method of heat treating steel mechanical elements having metal parts bonded therein by the contraction of the enclosing metal of the mechanical elements. The invention particularly provides for tightly securing auxiliary steel bearing or reenforcing parts in steel mechanical elements that are to be hardened by raising the temperature to a relatively high point, subsequent quenching and then drawing at a certain temperature depending on the hardness that is desired to produce within the body of the mechanical element.

In the conduct of the method involving my invention, the mechanical element is heated to a desired temperature, and the enclosed auxiliary parts are chilled, in advance of the quenching of the mechanical element, in such a manner that the metal of the parts will have desired reduced dimensions that approximate the dimension of the parts when at normal temperatures, which gives opportunity for the metal of the body of the mechanical element to freely contract and tightly secure the auxiliary parts within the body of the mechanical element when it is quenched and drawn. Thus the enclosed parts first chill when the metal of the body of the element tightly draws about the said parts, while, if the mechanical element is quenched without first chilling the parts, the metal of the element will be stretched, and the metal of the parts will be compressed and subsequent chilling of the parts by the conduction of the heat through the chilled body of the element will leave the parts loose within the body of the element. If desired, the temperature of the parts may be maintained to prevent excess chilling of the parts when the body of the element is chilled and thus prevent excess hardening of the parts.

The invention finds particularly advantageous results when used in the formation of steel tubular members, such as struts, tie-rod, axles, and other load carrying members, or pivotally connected parts of mechanisms.

The methods involved in my invention may be used for manipulating steel structures of different forms and which vary in their shape and details according to the uses to

which they are put. To illustrate a practical application of the invention, I have selected the method of forming the tubular axle wherein my invention finds particular advantageous results and wherein stub axle bearing members are enclosed or surrounded by the metal of the body of the axle, and also wherein reenforcing load carrying tubular members are located at the points in the axle to which the spring clamps or saddles are connected, as illustrative of the methods that utilize my invention, it being understood that the method particularly described may be modified in its details or steps of operation without departing from the spirit of the invention. As an aid in the description of the method of operation particularly referred to, I have illustrated, in the accompanying drawings, an axle, an auxiliary bearing and reenforcing parts. The process and the apparatus used in carrying out the processes are described hereinafter, as well as the article produced by the process.

Fig. 1 illustrates a view of a section of a trough having anvils and clamping members, and means for positioning the clamping members relative to each other to locate the centers in their proper relation to each other, and also to position the axes of the bushings in a definite relation to each other and to the body of the axle. Fig. 2 illustrates an enlarged view of an end part of the apparatus shown in Fig. 1 and indicates one of the steps in the process of heat treating the axle. Fig. 3 is an enlarged view of a transverse section of a part of the axle.

In the heat treatment of the axle, the temperature is raised to approximately 1500 degrees Fahrenheit and the axle is then quenched in water and drawn at a temperature of 1000 degrees to 1200 degrees Fahrenheit to produce an elastic limit of 140,000 to 160,000 pounds, but where axles contain members that are tightly enclosed in the body of the axle, quenching of the entire axle without previous heat treatment of such members, invariably results in producing a looseness between the surfaces of the members and the body of the axle, which produces a defective axle and, sooner or later, in the use of the axle,

the defect becomes apparent and often is magnified by reason of the fact that the play is increased by the strains or pounding to which it is subjected in the use of the axle.

5 In the preferred process embodying my invention, the members are chilled in advance of the quenching of the body of the axle by directing a chilling fluid against the members shortly before the axle is submerged in, or 10 covered by, a chilling fluid.

The particular axle shown in the drawings is tubular in form and is provided in its ends with bushings 2 that are enclosed by the metal of the axle 1 and so as to be completely 15 rounded thereby. The central parts of the axle are provided with reenforcing steel tubes 3 that are located within portions of the tubular axle 1 to which the spring saddles or the springs are secured for connecting the axle 20 to the vehicle. The tubes 3 preferably have a length sufficiently great to be enclosed by portions of the inner surface of the wall of the tube that are contiguous to the saddle or spring supporting portions 4 of the axle. The 25 spring supporting portions of the axle may be shaped to more efficiently engage and secure the spring saddles, or springs themselves, to the axle at the upper and lower sides of the axle as at 5. Also, if desired, the reen- 30 forcing tubes may be correspondingly shaped to more efficiently cooperate in the sustain- 35 ment of the load. Usually a bolt extends through the axle that is used for securing a spring saddle or a goose-neck to the axle and the axle is bored at this point, openings be- 40 ing formed through the upper and lower sides of the reenforcing tubes 3 and the body of the axle. If the spring saddle or the springs are 45 secured by U-bolts or clips, that surround the springs, or the spring saddles, small openings may be formed in the lower sides of the body of the axle and the reenforcing tubes 3 to permit introduction of the chilling fluid into the reenforcing tubes in advance of the quenching of the body of the axle.

In carrying out the process involving the use of my invention, I provide means for introducing water or steam, preferably, into the interior of the bushings 2 and the reenforcing tubes 3, in advance of the quenching of the body of the axle. Preferably, water in the form of a spray is directed into the bushings 2 through the lower ends of the bushings 50 and the steam is conducted away from the upper ends of the bushings, while the bushings and the ends of the axles are held clamped in their positions. Also, water is 55 preferably sprayed into the openings 7 formed in the lower sides of the reenforcing tubes 3 and the lower sides of the body of the axle 1. The steam may be conveyed away through the openings 8 formed in the upper sides of the reenforcing tubes 3 and the axle 60 65 1. Thus the tubes 3 may be chilled in advance

of the chilling of the body of the axle at the same time that the bushings 2 are chilled.

To heat treat the axle, it is first raised to a relatively high temperature and is then placed in a trough, such as that illustrated 70 in Fig. 1, which is provided with anvils 12 and 13, having upper surfaces that are shaped to conform to and to engage and secure end parts of the axle, and to secure load supporting parts of the axle and also clamping members 14 and 15 having clamping surfaces that conform to the upper surfaces of the end parts and the load supporting parts of the axle, whereby the said parts of the axle, when the axle is at the relatively high 75 temperature, will be forced into proper relation to each other with reference to the body of the axle. The parts of the axle will be forced into substantially the proper shape and any distortion will be removed by the 80 clamping of the said parts of the axle between the anvils 12 and 13, and the clamping members 14 and 15. Any suitable means may be provided for operating the clamping members. In the form of apparatus shown, the 85 clamping members are operated by suitable pneumatically or hydraulically actuated cylinders and pistons 16.

In order to fix the centers, particularly 90 of the bearing bushings 2, the trough is formed of two telescoping parts and in advance of the quenching of the axle, the anvils and their associated clamping parts may be shifted to either elongate or contract the 95 axle lengthwise to properly position the centers. This may also be performed pneumatically or hydraulically or by means of a 100 thread and nut mechanism connected to the ends of the trough. In the form of construction shown, a pneumatic means 18 is conventionally shown as connected to each 10 end of the trough. Thus in the quenching operation, the heated axle 1 may be placed on the anvils 12 and 13, the clamps 14 and 15 may be operated to clamp and properly align 11 the parts and then the clamps and anvils of one end of the trough may be drawn from, or moved towards, the clamps and anvils of the other end of the trough. The trough may then be flooded to quickly submerge the 12 axle and then evacuated to rapidly remove the water. The water may be introduced by suitable means formed in opposite sides of the trough, such as the openings 20, and the 13 water may be allowed to escape through suitable openings covered by the traps 21 for the quick submergence and the rapid discharge of the water, whereby all parts of the axle are subjected to substantially the same 14 chilling operation.

In order to chill the members enclosed by the metal of the body of the axle, the anvils 12 and 13 are provided with passageways 23 and 24 that communicate with the interior of the bushings 2 and the tubes 3, the 15

clamps 14 are also provided with the passageways 25 and 26, which also communicate with the interior of the bushings 2 and the tubes 3. Pipes 27 are connected together 5 and with the source of supply of water, whereby water or steam may be directed into the interior of the bushings and the tubes at the same time. Preferably, the passageways 23 and 24 terminate in nozzles 28 which will 10 operate to distribute, or spray, the cooling fluid in all directions. Water under pressure may be directed through the nozzles 28 and sprayed against the inner surfaces of the tubes and the bushings, and the steam allowed to escape through the upper pipes 29.

In the conduct of the process of heat treating the axle, subsequent to the location of the centers in their desired relation to each other, as described, water under pressure is directed 20 through the pipes 27 and, shortly thereafter, such as from three to five seconds, depending on the sizes of the auxiliary parts that are embedded in the body of the axle, the water is turned into the trough 10 to flood 25 the axle through the opening 20 and, when the axle has been chilled to the desired temperature, the gates 21 are open for quickly emptying the trough. The clamps 14 and 15 are then raised by the proper manipulation 30 of the valves that control the pressure within the cylinder 16 and the axle is removed and is replaced by a succeeding axle which is in turn subjected to the pressure of the clamps 14 and 15 against the anvils 12 and 13 and 35 the portions of the axle of each end having the bushing 2 and the tube 3 are forced into proper alignment and relation to each other and the centers of the parts of opposite ends are forced into their relation to each other 40 by the operation of the pressure in the cylinders 18. The water is then sprayed against the inner surfaces of the bushings 2 and the reenforcing tubes 3. When these have cooled 45 to a temperature that changes them into a solid, as distinct from semi-plasticity of the heated metal, the body of the axle is quenched by flooding the trough 10 as before. This produces an axle wherein the bearing bushing and the reenforcing tubes are tightly held 50 and enclosed by the surrounding metal of the hardened axle.

If desired, the steel of the bearing bushing may be formed of soft steel, such as the steel of bar stock metal having a low carbon 55 content, and the steel body of the axle may be formed of a steel having a high carbon content, such as that of S. A. E. No. 1045. A fluid having a desired temperature may be directed through the pipes 27 and 24 and 60 into the interior of the bearing bushings to gradually lower the temperature of the bushings or to maintain the temperature of the bushings within desired limitations for drawing or to maintain the metal of the bushings 65 relatively soft and to produce relatively soft

machinable bushings while the metal of the body of the mechanical element, or axle, is chilled. During the treatment of the bearing bushings, the metal of the body portion of the axle may be submerged or flooded, 70 that is, quenched, to chill the body of the axle to produce a hardened condition in the body of the axle. This may be regulated by regulating the drawing temperature. There will thus be produced a soft, machinable 75 bearing which, subsequent to the heat treating of the body of the axle, may be rebored or machined as may be desired. The softer metal of the bearing will thus be surrounded by the hardened elastic metal of the body of the axle. 80

The fluid is directed through the bearing members 2 and the axle reenforcing tubular part 3 to contract them in advance of the contraction of the surrounding metal of the body of the axle and prevent crushing of the bearing members and the reenforcing tubular parts while they are in the semi-plastic state, and the metal of the body of the axle is being chilled. By cooling the bearing members and the reenforcing tubular parts in advance of the chilling of the body of the axle, the metal of the body of the axle contracts about the solid members and reenforcing tubes to tightly enclose the same, and any amount of subsequent use of the axle 95 will not cause these parts to loosen from the metal of the axle.

I claim:

1. The process of forming a mechanical element which consists in enclosing metal auxiliary parts within the body of the metal of the mechanical element, subjecting the element and the parts to a relatively high temperature and directing a cooling fluid against 100 the auxiliary parts, and subjecting the body of the mechanical element to a cooling fluid.

2. The process of forming steel mechanical elements having steel bearing parts, the steel of the mechanical element having a carbon content different from that of the bearing parts, which consists in directing a temperature regulating fluid through the bearing parts for the desired length of time to maintain the desired drawing temperature in the 105 bearings, and quenching the body of the mechanical element to produce the desired hardening of the metal of the mechanical element while maintaining the metal of the bearing parts relatively soft and machinable by the 110 temperature regulating fluid directed through the bearing parts.

3. The process of forming a mechanical element which consists in enclosing metal auxiliary parts within the body of the metal of the mechanical element subjecting the element and the parts to a relatively high temperature and directing a cooling fluid against the auxiliary parts, shortly thereafter subjecting the body of the mechanical element to 115

a cooling fluid, and withdrawing the mechanical element from the cooling fluid at the desired temperature.

4. The process of forming steel mechanical elements having steel bearing parts, the steel of the body of the mechanical element having a carbon content different from that of the bearing parts, which consists in directing a temperature regulating fluid against the bearing parts for the desired length of time to produce the desired temperature in the bearings and subsequently quenching the body of the mechanical element to produce the desired hardening of the metal of the mechanical element.

5. The process of forming a tubular mechanical element having enclosed coaxial reinforcing members, which consists in subjecting the axle to a relatively high temperature, directing a cooling fluid against the reinforcing members and shortly subsequent thereto, quenching the body of the mechanical element.

6. The process of forming steel mechanical elements having auxiliary supporting parts enclosed in the metal of the body of the mechanical element, which consists in heating the body of the mechanical element to a relatively high temperature, forcing the said parts into definite relation to each other, clamping said parts to hold them in the said definite relation, directing cooling fluid against the surfaces of said parts, quenching the metal of the body of the mechanical element while the mechanical element is held in its clamped position.

7. The process of forming tubular axles having bearing members and reenforcing members located in end portions thereof, which consists in clamping said portions and forcing them into definite relation to each other, directing a cooling fluid against the surfaces of the said members, subsequently quenching the body of the axle while it is held in its clamped position.

8. The process of forming tubular axles, which consists in placing reenforcing tubular members within the vehicle supporting parts of the body of the axle and enclosing bearing members within the end parts of the axle, forming openings in the upper and lower sides of the said parts of the axle having the reenforcing tubes, directing a stream of the cooling fluid into the interior of the said members, subsequently quenching the body of the axle.

9. The process of forming tubular axles, which consists in locating reenforcing tubes within the vehicle supporting parts of the axle and enclosing bearing members in the end parts of the axle, heating the axle to a relatively high temperature, and directing a cooling fluid into the interior surfaces of the members, and subjecting the body of the axle to a cooling fluid.

10. The process of forming a tubular axle having bearing members in its ends, subjecting the axle to a relatively high temperature, clamping the end parts and forcing the bearing members into a definite relation to each other, subjecting the surfaces of bearing members to a cooling fluid and shortly thereafter quenching the metal of the body of the axle.

In witness whereof I have hereunto signed my name to this specification.
